(57) **CLAIM**

The ornamental design for a pair of earphones, as shown and described.

DESCRIPTION

FIG. 1 is a front perspective view of a pair of earphones showing my new design;

FIG. 2 is a rear perspective view thereof;

FIG. 3 is a front elevational view thereof;

FIG. 4 is a rear elevational view thereof;

FIG. 5 is a left side elevational view of each earphone of the pair of earphones;

FIG. 6 is a right side elevational view of each earphone of the pair of earphones;

FIG. 7 is a top plan view thereof; and,

FIG. 8 is a bottom plan view thereof.

The dash-dash broken lines in the drawings depict the portions of the pair of earphones which form no part of the claimed design.
